(57) **CLAIM**

The ornamental design for a three light flashlight, substantially as shown and described.

DESCRIPTION

FIG. 1 is a top, front, right side perspective view of a three light flashlight showing my new design;

FIG. 2 is a top plan view thereof;

FIG. 3 is a bottom plan view thereof;

FIG. 4 is a front elevation view thereof;

FIG. 5 is a rear elevation view thereof;

FIG. 6 is a right side elevation view thereof;

FIG. 7 is a left side elevation view thereof;

FIG. 8 is a bottom perspective view thereof; and,

FIG. 9 is a bottom, front, right side perspective view thereof, showing the crank handle in the charging position.

The broken lines in the drawings illustrate the portions of the design that form no part of the claim.
